TUBULAR WALL PLUG MADE FROM STRING OR LIKE MATERIAL

Filed Aug. 22, 1921

John Joseph Rawlings, ^{INVENTOR}
By *James L. Nease*
Attorney

UNITED STATES PATENT OFFICE.

JOHN JOSEPH RAWLINGS, OF LONDON, ENGLAND, ASSIGNOR OF ONE-HALF TO THE RAWLPLUG COMPANY LIMITED, OF LONDON, ENGLAND, A CORPORATION OF GREAT BRITAIN.

TUBULAR WALL PLUG MADE FROM STRING OR LIKE MATERIAL.

Application filed August 22, 1921. Serial No. 494,422.

To all whom it may concern:

Be it known that I, JOHN JOSEPH RAWLINGS, a subject of the King of Great Britain, residing at London, England, have invented new and useful Improvements Relating to Tubular Wall Plugs Made from String or like Material, of which the following is a specification.

It has heretofore been proposed to manufacture tubular wall plugs from strings, twines, or cords of suitable fibres, grouped side by side longitudinally and held together by an adhesive, and apparatus for the manufacture of such tubular wall plugs has been provided wherein separate strings or the like drawn from a spool holding creel, are gathered together side by side, passed through a tank in which the strings are coated with an adhesive, then passed through a die plate in combination with which a mandrel is provided in order to form the coated strings into a tubular bundle, and this bundle, after being dried and compressed, is finally divided into separate plugs by a suitable cutting device.

The tubular wall plugs thus produced are useful for enabling screws, nails and other fastening means to be secured in plaster, marble and other materials, the plugs being first inserted in holes formed for this purpose in the plaster or like material, and then the screw or nail is driven into the bore of the plug, whereby the fibres of the plug are pressed against the wall of the surrounding hole in the plaster or like material and the plug is thus held firmly in this hole whilst the bore of the fibrous plug affords a better grip for the screw or nail than would be obtained by driving the said screw or nail directly into plaster or like hard granular material.

The tubular wall plugs produced by the method of manufacture hereinabove referred to, are substantially cylindrical of uniform diameter from end to end and have flat ends. Now it has been found in the use of such a plug that there is some difficulty in insert-

ing it in a hole which is of about the same diameter as the exterior diameter of the plug. Moreover, when the hole into which a close fitting plug is to be inserted is formed in a gritty, friable or easily crumbled material, such as soft brick, stone, concrete, plaster and the like any loose material or dust in the hole is swept or pushed to the bottom of the hole by the plug as it is inserted therein thus necessitating making the hole of extra depth to accommodate such débris.

In order to mitigate these disadvantages, according to this invention, the plug is pointed or tapered at one end so that it can be more readily inserted in the hole by introducing this pointed or tapered end first.

The plugs may be pointed by means of automatically operating machinery in which, for example, the plugs are passed from a hopper into a hollow rotating lathe spindle along which they are propelled intermittently, each plug as it is brought to a position in which it protrudes from the spindle being gripped temporarily by a chuck by which it is held and rotated whilst the end of the plug is operated upon by a suitable knife tool, milling cutter or the like to form a tapered or pointed end to the plug, after which the plug is released by and ejected from the chuck. Machinery suitable for the purpose is in general well known and it is not essential to employ any particular type of machine. For example, the plugs may be pointed equally well by feeding them on to a rotating wheel by which they are caused to roll on a surface concentric with the wheel and whilst being so rotated the ends of the plugs may be carried round and operated upon by a milling cutter or like rotary tool to point their ends.

In the accompanying drawing, Figure 1 shows a cylindrical plug *a* with flat ends *b*. Figure 2 shows the improved plug *c* formed with one pointed end *d*. These plugs are composed of a number of strings *e* or the like laid side by side longitudinally as shown

in end view in Figure 3, secured together by an adhesive and compressed to a tubular form.

What I claim is—

- 5 A tubular wall plug comprising a plurality of strings extending side by side longitudinally of the plug to form a substantially cylindrical exterior surface, and layers of

an adhesive uniting together adjacent strings, the said plug having a diminishing tapered exterior surface at one of its ends.

JOHN JOSEPH RAWLINGS.
